APPARATUS FOR DEEP WELL PUMPING

Clarence J. Coberly, Los Angeles, Calif., assignor
to Roko Corporation, Reno, Nev., a corpora-
tion of Nevada

Application January 26, 1938, Serial No. 187,016

5 Claims. (Cl. 103—5)

My invention relates to the art of pumping a well, and more particularly to an apparatus for removing undesirable deposits from the walls of the well tubing.

5 Although my invention is susceptible of other uses, it is of particular utility in the oil industry and, accordingly, will be described in connection with such use, but it is to be understood that this is for the purpose of illustration only 10 and that I do not intend to be limited to such utilization of the invention.

My invention is especially adapted to be used in connection with a fluid operated deep well pump of the type disclosed in my Letters Patent 15 No. 2,081,220, issued May 25, 1937, entitled "Liquid operated pump", but any suitable type of fluid operated pump may be used without departing from the spirit of the invention.

In the oil well pumping art it has been found 20 that crude oil pumped from a well frequently has a high content of waxes or other undesirable materials which may, and commonly do, deposit on the walls of the well tubing to clog the tubing and reduce the flow of fluid through such tubing. For the purpose of this specification and 25 claims such materials are hereinafter referred to as "foreign materials". Crude oil as it is pumped from the bottom of a deep well ordinarily has a temperature sufficiently high to maintain any 30 wax or other similar substances in solution therein, but as the oil is pumped upwardly through the production tubing the temperature of the well formation and the oil temperature gradually decrease at different points along the tubing until the oil temperature falls below a critical point 35 at which at least a part of the wax therein crystallizes out in the form of a deposit on the walls of the tubing. Such deposit has been found to occur with certain oils when the temperature of the oil falls below 90° F. The level at which wax 40 begins to deposit on the tubing walls varies considerably in different wells and under different pumping conditions, and is determined by such factors, for example, as the character of the well 45 oil, the character of actuating fluid used in operating the fluid operated pump, the depth of the well, and the temperatures throughout the tubing. When a fluid operated pump is used, having a macaroni tubing conveying actuating fluid 50 to the pump and extending through the production tubing, wax normally deposits on the outside of such macaroni tubing and on the inside of the production tubing which carries the pumped oil to the surface of the ground. During 55 pumping, such wax deposit progressively in-

creases, requiring that the well periodically be shut down for considerable periods of time to permit the tubing to be cleaned of such deposit, and ordinarily necessitates removal of the pump from the well during such cleaning operations. The 5 accumulation of the wax deposit decreases the efficiency of the pump, and the periodic cleaning of the tubing is expensive and highly undesirable.

Accordingly, it is a primary object of my invention to provide a new and efficient apparatus 10 for cleaning well tubing of deposits of foreign materials thereon without removing the pump from the well.

It is a further object of my invention to provide an apparatus for cleaning well tubing of 15 deposits of foreign materials thereon during operation of the well pump.

A still further object of the invention is to supply a method and apparatus for cleaning well 20 tubing of deposits of foreign materials thereon, in which the well pump is utilized to actuate a cleaning element in the tubing.

Another object of the invention is to provide a 25 well tubing cleaning device adapted to reciprocate in a well tubing to clean such tubing of deposits of foreign materials thereon.

It is still another object of my invention to provide an apparatus for use in connection with a fluid operated pump in which actuating fluid for 30 the pump is conveyed downwardly through an outer tube of two concentric tubes to a point above the pump and is then conveyed downwardly from said point to said pump through the inner tube of said concentric tubes, the fluid 35 raised by the pump passing upwardly from the pump through the outer tube to said point and from said point upwardly through said inner tube.

A further object of the invention is to supply 40 an apparatus for pumping a well in which the deposit of foreign materials is controlled so that deposit will occur on only one tubular surface of the well tubing.

Still another object of my invention is to provide 45 an apparatus for use in connection with a fluid operated pump in which the production flow from the pump is utilized to actuate a cleaning device to clean the pump tubing of deposits of foreign materials, the production flow removing 50 such deposits from the tubing after they have been cleaned therefrom.

Another object of the invention is to provide a 55 novel apparatus for operating a fluid operated pump in which the production flow from the pump

- is conveyed upwardly through an inner tube and the actuating fluid is conveyed downwardly through an outer tube of a pair of concentric tubes.
- 5 A further object of the invention is to provide a novel form of device adapted to be dropped through a well tubing, and including means for introducing and removing such device from the tubing.
- 10 A still further object of my invention is to provide an apparatus for cleaning a tubing of foreign materials therein in which a cleaning element may be positively reciprocated in the tubing by fluid under pressure to remove the foreign materials.
- 15 Another object of the invention is to supply a cleaning element for a tubing, and to provide means for forcing the cleaning element longitudinally in either direction in the tubing. This is of particular importance in the event that the 20 cleaning element sticks in the tubing, since it provides means for removing the cleaning element without disturbing the position of the tubing.
- 25 Other objects and advantages of my invention will be apparent from the specification and drawing, in which:
- Fig. 1 is an elevational view, partly in section, of the upper end of my invention.
- 30 Fig. 2 is a sectional elevational view continued downwardly from the lower end of Fig. 1, but on a slightly larger scale.
- Fig. 3 is an elevational view, partly in section, of the pumping device of the invention, said view being a lower continuation of Fig. 2.
- 35 Fig. 1 shows an outer tubing 10 adapted to be extended downwardly into an oil well, having a tubing head 11 of any type well known in the art at the upper end thereof provided with a header connection 12 connected to a header 13 leading to a two-way valve 13a. Extending through the tubing head 11 and upwardly therefrom is the upper end 14 of an inner tubing 15, to which is threaded a T-joint 16. The T-joint 16 has 40 a pipe 17 connected to one branch thereof and an auxiliary header 18 connected to the other branch thereof in axial alignment with the inner tubing 15. Connected to the auxiliary header 18 is a gate valve 19 of standard design having 45 a gate valve member 20 adapted to be moved by a control wheel 21 so as to open or close the auxiliary header, as is well known in the art. Connected to the upper end of the auxiliary header 18, by means of a collar 22, is a tubular member 23 having a screw plug 24 in the upper 50 end thereof and having a delivery pipe 25 connected to and communicating with the tubular member. The other end of the delivery pipe 25 is preferably connected through a suitable T-joint 26 to the pipe 17, the pipe being provided 55 with a gate valve 27 between the T-joints 16 and 26 similar in construction to the gate valve 19, and the delivery pipe likewise being provided with a similar valve 27a. The other branch of 60 the T-joint 26 is connected through a pipe 28 to the two-way valve 13a, the valve having a supply line 29 and a discharge line 29a connected thereto. The two-way valve 13a is of any suitable type well known in the art, and has appropriate 65 passages therein, as shown in dotted lines 29b in Fig. 1, which are adapted to connect the supply line 29 to either the header 13 or the pipe 28, and the discharge line 29a to either the header 13 or the pipe 28, thus providing means for 70 reversing the flow through the device by rotation of 75

a handle 29c provided for that purpose. It will be understood that the supply line 29 leads to a suitable source of high pressure fluid (not shown), and that the discharge line 29a leads to a convenient point of discharge or storage of the 5 pumped fluid.

The tubing head 11 is preferably positioned above and adjacent the surface of the ground, and the outer tubing 10 is adapted to extend downwardly into a well. As shown in Fig. 2, the 10 outer tubing 10 is made up of an upper section 30, a central section 31, and a lower section 32, preferably connected together by threaded collars 33 and 34 respectively. The lower end of the inner tubing 15 is threadedly connected to 15 a transposition element 35 having an intermediate tubing 36 threadedly connected thereto and extending upwardly between the central section 31 of the outer tubing 10 and the inner tubing 15, the intermediate tubing making a fluid-tight 20 fit with an annular section 37 of the inner surface of the central section 31. The intermediate tubing 36 and the inner tubing 15 form a space 38 therebetween communicating at its upper end with a high pressure fluid space 39 defined by the 25 inner and outer tubings 15 and 10, and communicating at its lower end with a longitudinal passage 40 extending through the transposition element 35. The longitudinal passage 40 communicates at its lower end with the interior of 30 a lower section 41 of the inner tubing 15 which is threadedly connected to the lower end of the transposition element 35. It will be noted that the lower section 32 of the outer tubing 10 and the lower section 41 of the inner tubing define 35 a low pressure space 42 therebetween which communicates at its upper end with a space 43 between the transposition element 35 and the section 32, the space 43 communicating through an inlet passage 44 and a bore 45 formed in the 40 transposition element with the interior of the inner tubing 15 above the transposition element. Connecting the bore 45 and the space 38, and formed in the transposition element 35, is a reverse flow valve means 46, comprising a passage 45 47 suitably counterbored to receive a ball valve member 48 retained therein by a threaded sleeve 49, for a purpose which will be described herein-after.

As shown in Fig. 3, the lower section 32 of the 50 outer tubing 10 is provided with a conical seat 50 having an inlet opening 51 therein, the seat receiving the lower tapered end 52 of a pumping unit 53. The pumping unit 53, which is diagrammatically shown in the drawing, is of the 55 fluid actuated type as preferably shown in detail in my Letters Patent No. 2,081,220, referred to above, but any suitable type of pump may be utilized without departing from the invention. The pumping unit 53 is provided with inlet passages 54 and 55 having suitable inlet valves 56 therein, and with discharge passages 57 and 58 having suitable discharge valves 59 therein, the inlet passages communicating between the inlet opening 51 and the upper and lower ends of a 65 pump cylinder 60, and the discharge passages communicating between the upper and lower ends of the cylinder and the low pressure space 42. The pump cylinder 60 has a pump piston 61 reciprocable therein, connected through a piston 70 rod 62 with a motor piston 63 disposed in a motor cylinder 64. The motor cylinder 64 is provided with suitable high pressure fluid passages 65 and 66 adapted to supply high pressure fluid alternately to opposite ends of the motor piston 75

to reciprocate it, the flow of high pressure fluid being supplied by the lower section 41 of the inner tubing 15 and being controlled by suitable valve mechanism (not shown) in the pumping unit.

In Fig. 2 a cleaning element 70 is shown in the inner tubing 15. The cleaning element 70 has a tubular element 71 making a sliding fit with the inner tubing 15, and is provided at its upper end with a scraper member 72 threaded thereto. The scraper element 72 is provided with openings 73 therethrough, and has a central bore 74. The lower end of the tubular element 71 is provided with a seat member 75 threaded thereto, having vertical passages 76 therethrough and having a bore 77 in axial alignment with the central bore 74 of the scraper member 72. The lower end of the seat member 75 is provided with a chamber 78 and has orifices 79 communicating between the chamber and the interior of the inner tubing 15, and is also provided with a tapered seat 80 adapted to receive the upper tapered end 81 of a tubular plunger 82. The tubular plunger 82 is of slightly less diameter than the interior 25 of the inner tubing 15, so as to be readily movable therethrough, and has a helical vane 83 formed on the periphery thereof adapted to make a sliding fit with the interior of the inner tubing. Suitably connected to the upper end of 30 the tubular plunger 82 is a plunger rod 84 which extends upwardly, being journaled in the bore 77 and central bore 74, and having a cap 85 on the upper end thereof. The plunger rod 84 is of such a length that when the plunger 82 is seated 35 in the tapered seat 80 the rod will extend a substantial distance above the scraper element 72, downward movement of the rod and plunger relative to the tubular element 71 being limited by engagement of a collar 86 fixed on the rod and the scraper element. Loosely carried on the plunger rod 84, above the collar 86, is a flapper valve member 87 adapted to seat in a conical 40 valve seat 88 formed in the upper end of the scraper element 72. It will be noted that the flapper valve member 87 is free to move at all times relative to the seat 88, regardless of the position of the plunger rod 84.

In operation, high pressure actuating fluid is conveyed to the pumping unit 53 to operate it, the fluid normally flowing from a suitable source of supply through the supply line 29, the two-way valve 13a, the header 13, and the connection 12 into the high pressure space 39 between the outer and inner tubings 10 and 15. The actuating fluid flows downwardly through the space 39, through the space 38, and through the longitudinal passage 40, into the lower section 41 of the inner tubing 15, from whence it passes downwardly therein to operate the pumping unit 53, being alternately supplied through the high pressure passages 65 and 66 to the motor cylinder 64 to reciprocate the motor piston 63 therein. Since the motor piston 63 is operatively connected to the pump piston 61 by the piston rod 62, reciprocation of the motor piston causes reciprocation of the pump piston in the pump cylinder 60, to pump well fluid through the inlet opening 51, alternately through the inlet passages 54 and 55, and alternately through the discharge passages 57 and 58 into the low pressure space 42. The well fluid is then pumped upwardly through the low pressure space 42, the space 43, the inlet passage 44, and the bore 45 into the interior of the inner tubing 15 above the transposition element 35, through which it passes upwardly through the

upper end 14 of the inner tubing, the T-joint 16, the pipe 17, the two-way valve 13a, and the discharge line 29a, to a point of discharge or storage (not shown). During such pumping, the gate valves 19 and 21a are normally closed and the gate valve 27 is open. Attention is directed to the fact that the well fluid pumped from the pumping unit 53 normally flows upwardly through the outer tubing 10 to the transposition element 35 and thence flows upwardly through the inner tubing 15, whereas high pressure fluid flows downwardly in the outer tubing to the transposition element and thence through the inner tubing to the pumping unit, which is an important feature of the invention.

When it is desired to install and operate the cleaning element 70, which may be accomplished during normal operation of the pumping unit 53 with the valves 19 and 21a closed, the screw plug 24 is removed from the tubular member 23, and the assembled cleaning element is inserted into the tubular member as shown in dotted lines 90 in Fig. 1. The screw plug 24 is then reinserted into the tubular member 23 to close the upper end thereof. In practice, the cleaning element 70 drops by gravity through the tubular member 23 until the lower end of the tubular plunger 82 engages the gate valve member 20. The gate valve 19 is then opened by rotating the wheel 21 to move the gate valve member 20 out of alignment with the tubular member 23, and the cleaning element 70 is then free to drop by gravity through the inner tubing 15.

When the cleaning element 70 is started on its downward trip through the inner tubing 15 due to friction between the tubular element 71 and the inner tubing 15, the progress of the tubular element is retarded, and the tubular plunger 82 falls to its lowermost position in which the collar 86 engages the scraper element 72, so that the upper tapered end 81 of the plunger is out of engagement with the seat 80, permitting the free flow of well fluid upwardly around the tubular plunger as guided by the helical vane 83 and through the chamber 78, the vertical passages 76, the interior of the tubular element 71, the openings 73, and the scraper member 72, the fluid flow forcing the flapper valve member 87 outwardly and out of seating relation in the valve seat 88. The cleaning element 70 has a weight sufficient to carry it downwardly by gravity through the inner tubing 15 against the upward flow of well fluid therein. When the lower end of the tubular plunger 82 engages the upper end of the transposition element 35, the inertia of the cleaning element 70 causes the tubular member 71 to continue its downward movement until the seat 80 engages the tapered upper end 81 of the tubular plunger, at which time the free upward flow of well fluid past the tubular plunger is shut off, and the upward flow of well fluid starts to raise the cleaning element as a unit through the inner tubing 15. By reason of the orifices 79, a slight upward flow of well fluid is permitted to by-pass the tubular plunger 82, so that the rate of upward flow of the well fluid is slightly greater than the rate of upward travel of the cleaning element 70. As the cleaning element 70 moves upwardly through the inner tubing 15, the scraper member 72 scrapes the interior of the inner tubing to remove any deposit of foreign materials thereon, and since the upward travel of the well fluid is faster than that of the cleaning element, any foreign materials removed from the inner tubing 15 by the scraper member are carried

ahead of the cleaning element by the well fluid and discharged therewith.

During normal operation of the cleaning element 70, the gate valves 19 and 27a are preferably closed, and when the cap 85 engages the gate valve member 20, the upward pressure of the well fluid on the seat member 75 causes the seat member and the tubular element associated therewith to move upwardly relative to the tubular plunger 82 to unseat the tapered end 81 from the seat 80, which again permits a free flow of well fluid through the seat member 75 and permits the cleaning element to again drop by gravity through the inner tubing 15. Any foreign materials removed from the inner tubing 15 during the downward movement of the cleaning element 70 therein will be carried upwardly through the inner tubing by the flow of pumped well fluid therethrough, so that the cleaning action of the cleaning element may take place on both the upward and downward movements thereof.

It sometimes happens that the cleaning element 70 may stick in the inner tubing 15 intermediate its terminal positions, due to accumulation of foreign materials on the inner wall of the tubing, and it is very desirable to provide means for forcing the cleaning element through the tubing when this occurs. As described above, the cleaning element 70 is pumped upwardly through the inner tubing 15, and downward pumping of the cleaning element is permitted by the flapper valve member 87 and the two-way valve means 13a. When the cleaning element 70 sticks during its downward movement through the inner tubing 15, the fluid flow is reversed so as to pass fluid under high pressure downwardly through the inner tubing 15, which may be accomplished readily by rotating the handle 29c of the two-way valve 13a through an arc of 90° to connect the supply line 29 with the pipe 28 and the discharge line 29a with the header 13. Downward flow of high pressure fluid through the inner tubing 15 causes the flapper plate 87 to seat on the seat 88, and the cleaning element 70 is then pumped downwardly through the inner tubing, which overcomes any tendency which the cleaning element has to stick in the inner tubing. During downward pumping of the cleaning element 70, fluid in the inner tubing 15 below the cleaning element will be placed under relatively high pressure by the cleaning element, and will flow outwardly through the reverse flow valve means 46, displacing the ball 48 from its seat and flowing therearound into the space 38.

Before the cleaning element 70 reaches the transposition element 35, the two-way valve 13a is operated to reconnect the supply line 29 with the header 13 and the discharge line 29a with the pipe 28, to permit resumption of normal pumping operation in which the high pressure fluid passes downwardly into the outer tubing 10 and the production flow from the pumping unit 53 passes upwardly out of the inner tubing 15.

It will be understood from the foregoing description that during the normal pumping operation of the pumping unit 53 the cleaning member 70 may be utilized to remove foreign materials deposited on the inner surface of the inner tubing 15, the cleaning member automatically reciprocating the length of the inner tubing above the transposition element 35. Although I have shown a form of device in which the cleaning element 70 is directly actuated by operation of the pumping unit 53, which is the preferred embodiment of the invention, it will be appre-

ciated that any other convenient means may be utilized to actuate the cleaning element without departing from the invention. It will also be understood that in the preferred embodiment of the invention the transposition element 35 will be positioned in the well at a point just below the point at which foreign materials normally start to deposit out of the pumped well fluid, so that all of such deposit will occur on the inner wall of the inner tubing 15, thus confining such deposit to a desired wall from which it may readily be cleaned by means of the cleaning element 70. Furthermore, it will be apparent to those skilled in the art that the invention may successfully be employed under some operating conditions without the use of the cleaning element 70, it sometimes being convenient merely to remove from the well the upper portion of the inner tubing 15 by unscrewing it from the transposition element 35 and raising it out of the well through the outer tubing 10, to permit its being separately cleaned by any process well known in the art.

I claim as my invention:

1. In a deep well pumping device, the combination of: a pump adapted to be positioned in a well and operable to pump well fluid therefrom; well tubing adapted to receive said well fluid from said pump and convey it to the surface of the ground, said well fluid normally depositing foreign materials on a wall of said tubing; means for operating said pump; and a cleaning element adapted to be moved through said tubing for removing said foreign materials from said wall, said cleaning element being raised through the length of said tubing by the well fluid discharged from said pump.

2. In a fluid operated pumping device, the combination of: a pair of concentric well tubings, comprised of an outer tubing and an inner tubing; and a transposition element associated with said tubings at a point intermediate their ends for connecting said outer tubing above said point to said inner tubing below said point, and connecting said inner tubing above said point to said outer tubing below said point, said transposition element including valve means for connecting said inner and outer tubings at said point.

3. In a deep well pumping device, the combination of: a pump adapted to be positioned in a well and operable to pump well fluid therefrom; well tubing adapted to receive said well fluid from said pump and convey it to the surface of the ground, said well fluid normally depositing foreign materials on a wall of said tubing; means for operating said pump to pump well fluid upwardly through said tubing to the surface of the ground; and a cleaning element adapted to be dropped by gravity through said tubing to a predetermined point therein and then raised through said tubing by the rising action of said well fluid therein for removing said foreign materials from said wall during the operation of said pump.

4. In a deep well pumping device, the combination of: a pump adapted to be positioned in a well and operable to pump well fluid therefrom; well tubing adapted to receive said well fluid from said pump and convey it to the surface of the ground; an element adapted to be inserted into said tubing; means for pumping said element downwardly through said tubing; and means for utilizing the upward flow of well fluid through said tubing to raise said element through said tubing.

5. In a fluid operated pumping device, the combination of: a fluid operated pump positioned in a well and operable to pump well fluid therefrom, said pump having a discharge opening; an outer tubing; an inner tubing within said outer tubing; a transposition element associated with said tubings at a point intermediate their ends for connecting said outer tubing above said point to said inner tubing below said point and connecting said inner tubing above said point to said outer tubing below said point, said outer tubing below said point communicating with said discharge opening, the space between said outer and inner tubings above said point and said inner

tubing below said point forming a fluid passage for conducting high pressure fluid to said pump to actuate it, and said inner tubing above said point and the space between said outer and inner tubings below said point forming a discharge passage for said pump, so that foreign materials can be deposited on only one tubular wall of said discharge passage above said point; and means for cleaning foreign materials from the wall of said discharge passage above said point while well fluid is being discharged therethrough by said pump. 5 10

CLARENCE J. COBERLY.
